UPHOLSTERED CHAIR SEAT
CONSTRUCTION

Louis A. Suekoff, Wilmette, Ill.; Pauline G. Suekoff, administratrix of said Louis A. Suekoff, deceased, assignor to Nachman Spring-Filled Corporation, Chicago, Ill., a corporation of Illinois

Application July 25, 1932, Serial No. 624,579

1 Claim. (Cl. 155—179)

This invention relates to improvements in upholstered furniture seats and more particularly and specifically to improvements in seat cushion structures for chairs of the dining room type which are, as a rule, inadequately upholstered to render them comfortable, this being especially true of the cheaper and most commonly used chairs of this general type.

The main object of the present invention is to provide a chair seat equipped with a spring assembly of a very simple and efficient construction which includes means whereby the same may readily and durably be mounted upon the seat frame of a chair of the general type above-mentioned, and also includes means whereby said assembly may be shaped to suit the ideas of the manufacturer of such chairs to render the ultimate upholstered seat attractive in shape and comfortable to the occupant of the chair.

The objects of the invention include the provision of a seat frame and a spring assembly therefor which is relatively cheap and may be easily and quickly and, therefore, cheaply constructed, and which will afford the comfort and appearance of a generally far more expensive type of chair.

A suitable embodiment of the invention is illustrated in the accompanying drawings wherein:

Fig. 1 is a vertical sectional view of a spring assembly constructed in accordance with the invention.

Fig. 2 is a similar view showing a conventional chair seat equipped with a spring assembly of the type shown in Fig. 1.

Fig. 3 is a plan view of the chair seat shown in Fig. 2.

Figs. 4 and 5 are transverse sectional views, at right angles to each other, showing the invention embodied in a slip-seat frame for chairs.

This invention includes a conventional type of chair seat frame of a quadrangular type such as is usually found in dining room chairs. The latter are generally made of wood and include relatively light and shallow seat frames consisting of the four rails 1 of Figs. 2 and 3, and in some instances, said rails 1 are shaped to receive a slip-seat frame 7 such as is shown in Figs. 4 and 5.

In the manufacture of upholstered seat furniture wherein the seat upholstery includes springs, it is the usual and customary practice to secure supporting webs or other spring-supporting means to the lower edges of the rails of the seat frame or the slip-seat frame therefor. Owing

to the fact that the loads on the seats of such chairs tend to pull out the fastening means by which the spring supports are so secured, the said rails are required to be made relatively thick and heavy, and relatively long and strong nails or the like are required for securing the spring supports to the rails.

It is quite obvious that if the spring supporting means are secured to the upper edges or faces of the rails of the seat frames of chairs, smaller and lighter fastening devices may be used and appreciable economy be effected thereby. Additionally to this advantage, it is not necessary to invert the chair frame in order to secure the spring supporting means thereto and, in the case of those chairs which are equipped with leg-braces below the seat frame which interfere with the free swing of hammers, there is a further disadvantage in and objection to the use of spring supports secured to the lower edges of the rails because the operation of securing the same is far slower than that of securing the spring supporting means to the upper edges or faces of the rails of the seat frames.

It is also well known that fabric spring supports will stretch and sag more or less under the strain of seat loads. This stretching and sagging is more disadvantageous from the standpoint of appearance than from the purely practical viewpoint in that the said spring supporting means become too prominently visible from a short distance after having sagged, in the instances where such supporting fabric means are secured to the lower edges or faces of the chair seat frame rails, whereas, if the same are secured to the upper edges or faces of the rails of the seat frame, such sagging will not bring said fabric supports into view.

In constructing a chair seat in accordance with my invention, I employ a spring assembly comprising top and bottom fabric walls 2 and 3, each consisting of a single piece of fabric of far larger area than is occupied by the springs 4 interposed between the same substantially centrally thereof. These springs 4 are of equal sizes and of uniform strength and are suitably held in spaced relation to each other.

In the instance illustrated, the springs 4 are contained in pockets or rectangular cells formed by means of fabric strips 5 and 6, extending transversely of each other and which are stitched along their top and bottom edges to the walls 2 and 3 as, for example, is shown and described in the Letters Patent to L. A. Suekoff No. 1,411,227. However, any other suitable means may

be used to maintain said springs 4 in proper relative positions without departing from the invention.

The springs 4 are disposed within a rectangular area which is preferably appreciably smaller than that bordered by the rails 1 of the seat frame, while the top and bottom walls 2 and 3 of the spring assembly are of appreciably greater area than that of the seat frame.

10 The said walls 2 and 3 may be of burlap or of other strong, durable, and relatively cheap material capable of sustaining heavy seat loads without tearing.

In the instance illustrated in Figs. 1, 2, and 3, 15 the marginal portions of the top and bottom walls of the spring assembly are forced into contact with each other along lines substantially coincident with the size and contour of the upper face of the seat frame in such manner as will 20 partially compress the marginal springs of the group and produce a finished structure having the general shape of a bed-pillow, wherein the group of springs is centrally disposed.

This bringing together of the marginal portions 25 of the walls 2 and 3 is effected along lines imprinted upon the outer faces of said marginal portions, at the time of securing the latter to the upper edges or faces of the rails 1, by means of tacks or the like inserted through said marginal portions along said imprinted lines and which are driven into the rails 1.

The bottom wall 3 of the spring assembly thus becomes the spring and load supporting element 30 and, therefore, is preferably made of a heavier or stronger fabric than the wall 2. Furthermore, the said marginal portions of the walls 2 and 3 may be folded over along lines immediately outwardly of the imprinted lines to afford further 35 resistance to rupture by the tacks under the influence of load on the seat cushion.

After thus mounting the spring assembly upon 40 the seat frame, the padding and cover fabric are supplied to provide a finished cushion. The latter is thus equipped with load supporting springs disposed in proper position to bear the load of 45 the weight of the occupant and yield thereto to a far greater and more comfortable extent than is usual in the case of upholstered seat chairs of the dining room type, and particularly of the 50 smaller or armless chairs of this type.

In the case of slip-seat frames 1, such as are shown in Figs. 4 and 5, wherein the rails are 55 relatively wide and border a central quadrangular opening of less area than in the case of seat frames of the type shown in Figs. 1, 2, and 3, it is preferable to secure the bottom wall 3 to the upper faces of the rails along the marginal portions of the said bottom wall along lines spaced from the seat frame opening and also spaced 60 from the outer edges of the rails and from the lines along which the marginal portions of the top wall 2 of the spring assembly are secured to the upper faces of the said rails as clearly shown by the respective sets of tacks 8 and 9, or the 65 like, as shown in Figs. 4 and 5.

In practice the said marginal portions of the lower wall 3 are first secured to the upper face of the seat frame 1 in such position as to determine the ultimate plane of support for the springs 4, the portion 10 of the fabric being somewhat slack before the marginal portions of the top fabric 2 are secured in place as shown.

The springs 4 are maintained compressed to the requisite degree to determine the plane of the top face of the spring assembly after driving the tacks 9 or the like into place, said springs being maintained in such compressed condition during the operation of driving the said tacks 9.

In both structures, the marginal portion of the top fabric between the tacks 9 and the group of 15 springs 4, is spaced from the marginal portion of the bottom fabric, and, in the structure of Figs. 4 and 5, said top fabric is also spaced from the top face of the seat frame. Air spaces are thus provided in the marginal portion of the assembly 20 over which the marginal portions of padding and cover fabric are disposed and are normally firmly supported. These marginal portions of said padding and cover fabric yield readily to the sagging of the middle portions under the influence 25 of load.

In the light of the foregoing statements of objects of the invention, and the explanation of the disadvantages incident to chairs wherein the spring supporting means are secured to the lower edges of the rails of the seat frame, the advantages of the present invention will be readily understood and appreciated.

I claim as my invention:

A chair seat comprising a seat frame presenting an opening, a spring assembly comprising a pair of fabric sheets having free marginal portions and having central portions constituting the top and bottom walls of a casing, partition and division walls extending transversely to each other secured at their top and bottom edges to said central portions of said fabric sheets and cooperating with the latter to form a plurality of rows of individual substantially square cells, each spaced from the next adjacent cell by a single thickness of fabric and all of which are spaced from the peripheral edge portions of said sheets and covering an area less than that of the opening in the seat frame, upholstery springs of equal length and strength and of greater length 50 than the height of said cells filling all of the latter, the marginal portions of said fabric sheets being secured to the seat frame in relative positions to cause the lower sheet to sag in said opening and provide a support for said springs well below the plane of the upper face of the seat frame, and said upper sheet being bellied above the said plane and maintained under tension for cooperation with the lower fabric sheet to maintain the marginal springs of said cells 55 under constant compression to a greater extent than the remaining springs to provide a substantially pillow-shaped yielding support within the opening of said seat frame.

LOUIS A. SUEKOFF. 65
